FLAT STEREOTYPE METAL DISTRIBUTOR

William L. Crawford, Plainfield, N. J.

Application January 28, 1935, Serial No. 3,832

12 Claims. (Cl. 22—2)

The invention relates to apparatus for the casting of stereotype plates and more particularly to equipment for the delivery and distribution of the casting metal to a stereotype casting box.

5 The primary object of my invention is to provide a stereotype casting apparatus by which molten metal is received from a melting pot and delivered to a stereotype casting box in a particularly practical and satisfactory manner, in which apparatus means are provided for the return to the melting pot of any excess metal.

10 A further object of my invention is to provide in apparatus of the character described means for dispensing the molten metal by which to simultaneously disperse the slag or other foreign matter in the molten metal, thus to prevent the entrance of same into the distributing apparatus.

15 Another object of my invention is to provide a stereotype casting apparatus comprising means for the selective distribution of the molten metal into a stereotype casting box by which to obviate the various objectionable results now occurring in such processes so as to produce a superior stereotype plate.

20 The invention will be fully and comprehensively understood from a consideration of the following detailed description when read in connection with the accompanying drawings which 25 form part of the application, with the understanding, however, that the improvement is capable of extended application and is not confined to the exact showing of the drawings nor to the precise construction described and, therefore, such changes and modifications may be 30 made therein as do not affect the spirit of the invention nor exceed the scope thereof as expressed in the appended claims.

35 In the drawings:

40 Fig. 1 is a side elevational view illustrating the practical use of my apparatus in conjunction with a melting pot and a stereotype casting box.

Fig. 2 is a longitudinal vertical section view 45 thru the distributor arm of my apparatus.

Fig. 3 is a plan view, partly broken away, in section of the distributor arm as shown in Fig. 2.

Fig. 4 is a plan view of the distributing head; and

Fig. 5 is an end elevational view of the distributing head, as shown in Fig. 4, partly broken away.

50 Referring now to the drawings for a more detailed description thereof, and particularly to Fig. 1, illustrating the general arrangement and 55 application of my apparatus, a brief description

of same follows. It will be noted that two positions of the apparatus illustrated are shown. The position illustrated in full lines illustrates the apparatus arranged for the delivery of metal to the casting box. The dotted line position of the apparatus shows same in its inoperative position, the casting box being open preparatory to the removal of the finished stereotype plate. The numeral 6 indicates a metal melting furnace, the metal pot 7 of which contains an adequate supply of molten stereotype casting metal. My stereotype casting apparatus comprises in general a base 8 upon which is vertically supported a standard 9 having an adjustable bracket 10 secured thereon. The bracket 10 includes a pair 15 of arms 11 upon which a distributor arm 12 is swingably mounted by means of the trunnions 13. The distributor arm 12 comprises in general an intermediate tubular structure 14 at one end of which is provided a metal receiving ladle 15. To 20 the opposite end of the intermediate structure 14 is affixed a distributing head 16, from which molten metal is supplied to a conveniently arranged stereotype casting box 17.

25 Since the stereotype casting box 17 illustrated is of the usual construction and arrangement now in general use, a detailed description of same is not required. It is however to be noted that the hingedly connected members 18 comprise the casting mold for the formation of the stereotype plate in conjunction with a matrix 19 disposed therein. The free edge of one of the members 18 is bevelled so as to form a tunnel-like structure for the reception of the molten metal from the distributor apparatus of my invention. 30 The stereotype casting box, as illustrated, is of the type designed to produce flat stereotype plates. It will however be obvious after a more detailed description of my apparatus is given that by an appropriate arrangement of some of the elements 35 therein the apparatus may be readily adapted for use in conjunction with curved or semi-cylindrical stereotype plates.

40 The trunnions 13 provide for the swinging of the distributor arm 12 so as to adjust the elevation of the distributor head 16 in relation to the casting box 17, and likewise to facilitate the dipping of the ladle 15 into the molten metal within the melting pot 7. To further assist in the manipulation of the distributor arm 12 a counterbalance is provided which comprises a flexible cable 20, one end of which is attached to the distributor end of arm 12. A sheave 21 rotatably mounted on the upper portion of standard 45 50 55 9 guides in the cable 20 as the arm 12 is swung

in either direction. A counterweight 22 is secured to the other end of cable 20 by which to hold the distributor arm 12 in any desired position. An adjustable rod 23 mounted on bracket 10 and 5 engaging with the distributor arm 12 in its lowermost position provides a positive stop for same.

A detailed description of the distributor arm 12 of my apparatus now follows, during which attention is directed particularly to Figs. 2 and 3. 10 As aforementioned, the distributor arm 12 comprises the intermediate tubular structure 14, the metal receiving ladle 15 and the distributor head 16, the joint function of which is to receive and convey from a suitable melting pot 7 the molten 15 metal and to deliver same via the distributing head to the stereotype casting box. The metal receiving ladle 15, disposed at one end of the arm 12, is preferably of cylindrical shape, the sides of which converge into a constricted passage 24, 20 the axis of the ladle being transverse to the arm 12. An oblong aperture 25 is provided in the upper portion of the ladle 15 from the rear edge of which extends a plate 26, the upper surface of which is tangential with the periphery of the 25 ladle 15 and in substantial parallelism with the longitudinal axis of the arm 12. The edge of the plate 26 parallel to the longitudinal side of the aperture 25 is bevelled so as to provide a sharp edge 27. A function of the plate 26 is to remove 30 or disperse the slag floating on the surface of the molten metal during the dipping of the ladle 15. This action is illustrated in Fig. 1 from which it will be apparent that as the ladle 15 is being submerged the edge 27 is the first portion of the 35 plate 26 to be submerged. During the lowering of the ladle 15 the edge 27 cuts a line in the slag surface of the molten metal and thereafter an appreciable area of the molten metal surface is cleared, the slag becoming entrapped below the plate 26 or dispersed beyond same. When the 40 entire ladle is submerged to receive the metal into the aperture 26 the metal will naturally flow from the region of the cleared surface thus to prevent any slag entering the ladle 15.

In order to permit the control of the molten metal from the ladle 15 into the distributor arm 45 a valve 28 is provided. This valve is of the rotatable tapered plug type, the axis of which is arranged transverse of the arm 12. The nuts 29 provide adjustment for the tapered plug of the 50 valve 28, which is provided with a thru radial slot 30 in registry with the passage 24. To facilitate the convenient operation of the valve 28 from a position normally occupied by the operator a 55 valve operating mechanism is provided which comprises an arm 31 fixedly attached to the valve plug, a connecting rod 32 and a lever handle 33 arranged and connected substantially as shown in Fig. 1. The lever 33 is positioned for the convenience of the operator near the distributing head of my apparatus and is pivotally mounted on the arm 12. The connecting rod 32 has its ends hingedly connected respectively to the lever handle 33 and the valve arm 31. The valve 28 is 60 provided with stops, not shown, by which the full open or closed position of said valve is determined.

Attention is directed to Fig. 2 in which the structure and arrangement of the intermediate member 14 and the distributing head 16 are 65 shown. In both of the members 14 and 16 a pair of longitudinal passage-ways is provided. The upper passage-way 34 connects at one end with the valve 28, the other end thereof terminating 70 in the interior of the distributor head 16 thru an

abrupt vertical passage 35. The lower passage-way 36 extends from the interior of the distributor head 16 to terminate obliquely as at 36a outside the member 14. The terminal 36a is so disposed near the ladle end so that metal passing 5 thru the lower passage 36 is delivered into the melting pot 7.

The sides and bottom of the passage 36 diverge toward the distributing head 16 so as to form therein a reservoir 37, the capacity of which is 10 adequate to contain sufficient molten metal to complete the casting of an entire stereotype plate. The function of the passages 34, 35 and 36 in cooperation with the ladle 15 and the reservoir 37 15 will be more obvious from an inspection of Fig. 1 in which both the operative and inoperative positions of the distributor arm 12 are illustrated. As previously described, the metal is received into the ladle 15 while the distributor arm 13 is in an appropriate oblique position, the valve 28 being 20 closed. The distributor arm 12 is then swung down to approximately horizontal position so that the distributor head 16 thereof is in position over the stereotype casting box 17. The valve 28 is 25 then opened by swinging the lever handle 33 whence the metal runs thru the upper passage 34 and the vertical passage 35 into the reservoir 37, the arm 12 being at a sufficient inclination to permit the free running of the molten metal. The metal is then decanted from the reservoir 30 37 by means hereinafter described. In order to insure an adequate supply of molten metal a greater quantity than is actually required is conveyed to the reservoir 37. After the casting process has been completed the excess metal is 35 returned to the melting pot 7 by again raising the distributor head or the arm 12 so that the excess metal remaining in the reservoir 37 will flow back to the melting pot 7 thru the lower passage 36. It is of course obvious that in order to prevent 40 the chilling of the metal during this handling that the distributor arm 12 may be equipped with such auxiliary heating elements and suitable insulating material as to prevent the occurrence of this effect.

The detailed description of the arrangement and controlling mechanism of the distributor head 16 now follows, during which attention is directed to Figs. 2, 4 and 5. It is to be observed that the function of this portion of my apparatus 45 is to regulate and control the supply of the molten metal into the stereotype casting box as desired by the operator. For this purpose a series of valves 38 of the tapered plug type are arranged in a row across the vertical end of the distributor head 16. The axes of valves 38 are in substantial parallelism with each other and approximately at right angles to the longitudinal axis of the arm 12. The numeral 39 indicates the rotatable 50 valve plug which has an axial bore 40 extending 55 from its lower end which when the valve is in open position is connected to the reservoir 37 thru the port 41. The port 41 is cut thru the end wall of the distributor head 16 and thru the body of the valve 38 to terminate in the axial bore 40 of 60 the valve plug. Each valve 38 is equipped with a lever arm 42, which arm is free to rotate on the shank of the valve plug 39, the engagement of these members being effected by the insertion of a 65 slideable pin 43. The pin 43 is slidably mounted in the center portion of the lever arm 42 and is provided with grooves 44 which, in conjunction with the ball catch 45, determine the position of the pin 43.

A block 46 attached to the pin 43 and slidably 75

5 mounted in a slot 47 provides a convenient means for moving the pin 43, which when it is pushed forward engages the lever arm 42 onto the shank of the valve plug 39 and in the retracted position 5 disengages these members.

10 In order to provide for operation of all of the valves at one time a cross bar 48 is disposed laterally of the distributor head to slide in blocks 49 and has each of the lever arms 42 pivotally connected to it by means of the stud screws 50 15 slidably engaged in slots 51 cut in the lever arm 42. One of the arms 42 is extended to cooperate with a quadrant 52 in which a series of holes 53 are arranged to receive a stop 54 by which the extent of the opening in the valves 38 may be predetermined. A tension spring 55, having its ends respectively attached to the distributor head 16 and the cross bar 48, urges the latter to the left, as shown in Fig. 4, thus to close the valves. 20 A convenient means is arranged on the cross bar 48 so that the valves may be held in open position and instantly closed as desired by the operator. This means comprises a post 56 pivotally mounted on the bar 48, into which is fitted 25 a set screw 57 adapted to engage a stop bar 58 slidably retained in the post 56. A leaf spring 59 carried on the bar 48 presses the right end of the stop bar 58 downward against a stop 60. A stop block 61 is mounted on the distributor head 16 to provide a shoulder against which the stop bar 58 engages in normal position. In considering the operation of the distributor head valve mechanism it is to be observed that the valves as shown in Fig. 4 are in closed position and in 30 Fig. 5 are in open position. In preparation for the pouring or charging process the stop bar 58 is locked in the post 56 in such position as to determine the extent of the opening of the valves 38 when the latter is engaged with the block 61. 35 The stop 54 on the quadrant 52 may assist in this setting. The cross bar 48 is then moved to the right by the handle 62 until the end of the stop bar 58 engages with the block 61, when the handle 62 is released. The valves are thus opened 40 to a predetermined position, as shown in Fig. 5, during which the metal in the reservoir 37 is being delivered to the stereotype casting box 17. As soon as the casting is completed the operator may instantly close all of the valves by pressing 45 down the right end of the stop bar 58, whence the spring 55 moves the cross bar 48 to the left, thus closing the valves, as shown in Fig. 4.

To facilitate the even distribution of the metal from the respective valves 38 into the casting 55 box 17 an elongate funnel 63 is mounted on the lower portion of the distributor head 16. The sides of the funnel 63 are disposed at an oblique angle to diverge into an enlarged opening at the top thereof to receive the molten metal from the valves 38. To further assure the even distribution of the metal in flowing thru the funnel 63 the lower side of the funnel is provided with a series of convex mounds 64 suitably arranged in relation to the bore 40 of the valve 38 so as to cause the metal issuing from same to be diffused or spread out as illustrated in Fig. 5. The funnel 63 will thus cause the molten metal issuing from the distributor head 16 to be supplied to the casting box 17 in a continuous ribbon-like stream so that the entire breadth of the casting box form receives a uniform amount of metal at the same time. This feature of supplying the molten metal into the stereotype casting box assures a superior product.

75 In order to prevent the waste and annoyance

of metal dripping from the funnel 63 after the completion of the process a drip tray 65 is pivotally mounted on the distributor head 16 by the pivots 66. The tray 65 is arcuate in cross-section so that when swung under the funnel 63, as shown 5 in dotted line in Fig. 1, the tray may receive the metal dripping from the funnel. In the operative position the tray 65 is swung to the position shown in full line in Fig. 1 by moving the lever handle 67. 10

What is claimed as new is:

1. In a machine of the character described, means swingably mounted and including a ladle adapted to be dipped into a melting pot containing molten metal, said means including also a body extending forwardly from said ladle, said body having a passageway thru which metal may flow from said ladle by tilting of said means in the appropriate direction, said means including a reservoir into which the metal may flow from 20 said passageway, said means further including a part having a second passageway below said first passageway and extending rearwardly from said reservoir and adapted to return unused metal into the melting pot. 25

2. In a machine of the character described, means swingably mounted and including a ladle adapted to be dipped into a melting pot containing molten metal, said means including also a body extending forwardly from said ladle, said body having a passageway thru which metal may flow from said ladle by tilting of said means in the appropriate direction, said means including a reservoir into which the metal may flow from 30 said passageway, said reservoir having a series 35 of discharge orifices thru which metal may flow into a stereotype casting box, and a series of valves in said orifices.

3. In a machine of the character described, means swingably mounted and including a ladle adapted to be dipped into a melting pot containing molten metal, said means including also a body extending forwardly from said ladle, said body having a passageway thru which metal may flow from said ladle by tilting of said means in the appropriate direction, said means including a reservoir into which the metal may flow from said 40 passageway, said means further including a part having a second passageway below said first passageway and extending rearwardly from said reservoir and adapted to return unused metal into 45 the melting pot, said reservoir having a series of discharge orifices thru which metal may flow into a stereotype casting box, and a series of valves in said orifices. 50

4. In a machine of the character described, means swingably mounted and including a ladle adapted to be dipped into a melting pot containing molten metal, a plate extending from the upper edge of said ladle and tangential with the periphery thereof, a body extending forwardly from said ladle, said body having a passageway thru which metal may flow from said ladle by tilting of said means in the appropriate direction, said means including a reservoir into which the metal may flow from 60 said passageway. 65

5. In a machine of the character described, means swingably mounted and including a ladle adapted to be dipped into a melting pot containing molten metal, said means including also a body extending forwardly from said ladle, said body having a passageway thru which metal may flow from said ladle by tilting of said means in the appropriate direction, said means including a reservoir into which the metal may flow from 70 said passageway. 75

passageway, said reservoir having a series of discharge orifices thru which metal may flow into a stereotype casting box, a series of valves in said orifices, and means secured to said reservoir and 5 extending downwardly and forwardly therefrom and adapted to receive metal from said discharge orifices.

6. In a machine of the character described, means swingably mounted and including a ladle 10 adapted to be dipped into a melting pot containing molten metal, said means including also a body extending forwardly from said ladle, said body having a passageway thru which metal may flow from said ladle by tilting of said means in 15 the appropriate direction, said means including a reservoir into which the metal may flow from said passageway, said reservoir having a series of discharge orifices thru which metal may flow into a stereotype casting box, a series of valves in 20 said orifices, and means secured to said reservoir and extending downwardly and forwardly therefrom and adapted to receive metal from said discharge orifices, the last-mentioned means including means for distributing or diffusing.

25 7. In a machine of the character described, means swingably mounted and including a ladle adapted to be dipped into a melting pot containing molten metal, said means including also a body extending forwardly from said ladle, said 30 body having a passageway thru which metal may flow from said ladle by tilting of said means in the appropriate direction, said means including a reservoir into which the metal may flow from said passageway, said reservoir having a series 35 of discharge orifices thru which metal may flow into a stereotype casting box, a series of valves in said orifices, and means for controlling all of said valves simultaneously.

40 8. In a machine of the character described, means swingably mounted and including a ladle adapted to be dipped into a melting pot containing molten metal, said means including also a body extending forwardly from said ladle, said 45 body having a passageway thru which metal may flow from said ladle by tilting of said means in the appropriate direction, said means including a reservoir into which the metal may flow from said passageway, said reservoir having a series 50 of discharge orifices thru which metal may flow into a stereotype casting box, a series of valves in said orifices, means for controlling all of said

valves simultaneously, and means for holding said controlling means at a selected position.

9. In a machine of the character described, means swingably mounted and including a ladle 5 adapted to be dipped into a melting pot containing molten metal, said means including also a body extending forwardly from said ladle, said body having a passageway thru which metal may flow from said ladle by tilting of said means in the appropriate direction, said means including a 10 reservoir into which the metal may flow from said passageway, said reservoir having a series of discharge orifices thru which metal may flow into a stereotype casting box, a series of valves in said orifices, and means for controlling all of 15 said valves simultaneously, each of said valves including means connecting it with said control means and readily disconnectible therefrom.

10. In a machine of the character described, means swingably mounted and including a ladle 20 adapted to be dipped into a melting pot containing molten metal, said means including also a body extending forwardly from said ladle, said body having a passageway thru which metal may flow from said ladle by tilting of said means in 25 the appropriate direction, said means including a reservoir into which the metal may flow from said passageway, said reservoir having a series of discharge orifices thru which metal may flow into a stereotype casting box, a series of valves 30 in said orifices, means secured to said reservoir and extending downwardly and forwardly therefrom and adapted to receive metal from said discharge orifices, and a pivotally mounted plate adapted to be swung under said forwardly and 35 downwardly extending means.

11. In a machine of the character described, a reservoir having a series of discharge orifices thru which metal may flow into a stereotype 40 casting box, and a series of valves in said orifices, said series of valves having means for diffusing the molten metal.

12. In a machine of the character described, a reservoir having a series of discharge orifices 45 thru which metal may flow into a stereotype casting box, and a series of valves in said orifices, and distributing means secured to said reservoir and extending downwardly and forwardly therefrom, and diffusing means on said distributing means whereby to diffuse the molten metal discharged from said orifices.

WILLIAM L. CRAWFORD.
